UNITED STATES PATENT OFFICE.

OLIN S. PROCTOR, OF DENVER, COLORADO, ASSIGNOR, BY MESNE ASSIGNMENTS, TO THE TERRY, TENCH & PROCTOR TUNNELING MACHINE COMPANY, A CORPORATION OF NEW YORK.

TUNNELING-MACHINE.

No. 900,950.

Specification of Letters Patent. Patented Oct. 13, 1908.

Application filed February 26, 1907. Serial No. 369,533.

To all whom it may concern:

Be it known that I, OLIN S. PROCTOR, a citizen of the United States of America, residing in the city and county of Denver and State of Colorado, have invented a new and useful Tunneling-Machine, of which the following is a specification.

My invention relates to improvements in tunneling machines; and the objects of my invention are: First, to provide a rotary tunneling machine in which a plurality of rock drilling engines are arranged in rows that extend from the central portion of the cutter head to its peripheral portion, and in such a coöperative relation when in operation as to produce a circular tunnel. Second, to provide an automatic tunneling and muck discharging machine. And third, to provide a simple, practical, multiple drilling engine 20 rotary tunneling machine that will automatically collect the rock muck at the breast of the tunnel and convey it to and discharge it from the rear end of the machine. I attain these objects by the mechanism illustrated 25 in the accompanying drawings, in which

Figure 1, is a side elevation, partly in section, of the improved tunneling machine. Fig. 2, is a plan view thereof. Fig. 3, is a front elevation of the cutter head and the 30 cylindrical casing which incloses the same. Fig. 4, is a central, horizontal sectional view of the cutter head, on the line 4—4 of Fig. 3, showing a portion of the supporting frame and of the belt conveyer, which receives and 35 discharges the muck. Fig. 5, is a vertical, sectional view on the line 5—5 of Fig. 1. Fig. 6, is a similar view on the line 6—6 of Fig. 1. Fig. 7, is a vertical, sectional view through the cutter head, at right angles to 40 the section shown in Fig. 4. And Fig. 8, is a sectional view through one of the arms of the cutter head, showing the hammer pistons and their cylinders, the drills, and the branch ports connecting the several cylinders, with a 45 main supply port.

Referring to the drawings, the numeral 15, designates the main supporting frame of my tunneling machine. This supporting frame consists of a beam of metal preferably steel, 50 the under side of the front end of which is provided with an axle 15^a, which is secured to it by a box 15^c, which is bolted or otherwise secured to the under side of the frame.

Upon the opposite ends of this axle I mount 55 wheels 15^b, which support the forward end

of the beam frame. The opposite end of the frame 15, is supported by a jointed connection to a supplementary frame 17, which is mounted on track wheels 17^a, that are secured to the opposite ends of axles 17^b that 60 are secured by boxes to the under side of the frame 17.

The jointed connection between the main frame 15 and the supplementary frame 17 is adapted to permit a vertical and lateral adjustment of the main supporting frame above and below and to either the right or left hand side of the central horizontal plane of the track wheel supporting axles of the main and supplementary supporting frames. This 70 joint comprises a loop 18, which is secured by bolts 22 to the rear end of the main frame. This rear side of this loop is provided with a vertical row of apertures 19, 20, and 21. The aperture 20 is positioned in horizontal 75 alignment with the center of the main supporting frame, and the apertures 19 and 21 are placed above and below it respectively and at equal distances from it. A pin 22 is adapted to fit in these apertures, and is 80 shown in the aperture 20. This pin is provided with a head portion 22^a, to which a strap 22^b is secured by bolts 22^c. The head of the pin is bolted to a cross bar 25, on the front end of the supplementary frame 17, by 85 the strap 22^b and bolts 22^c. The inner end of the pin 22 is secured to the apertures by a vertical pin 24, which passes through it close to the inside surface of the rear side of the loop. When the pin 22 is in the aperture 20 90 of the loop, and at the same time in the center of the width of the cross bar of the supplementary frame, the main frame stands in a horizontal plane, and will bore a straight 95 tunnel, but if it is desired to bore a tunnel with an upward grade the pin is moved to the upper aperture 19 of the loop, which will lower the rear end of the main frame and incline its front end upward; and if the pin 22 is placed in the aperture 21 it will raise the 100 rear end of the main frame and lower its front end. The main frame can be moved in either direction, relatively to the position of the frame 17, by loosening the strap 22^c, on the cross bar, and sliding the pin on the 105 said bar to one side or the other as desired, which movement will cause the forward end of the main frame to point to either the right or left of the horizontal center of its track wheels.

While I have illustrated but one pin aperture in the loop above the horizontal position of the pin and main frame, my invention contemplates enough to give to the machine any practical range of different grades of tunnel inclination. The main supporting frame of my machine is provided with a pair of raised journal boxes 14, positioned one at the front or cutter head end of the frame and 10 the other adjacent to its rear end, in which a tubular shaft 13 is rotatably journaled. The rear end of this tubular shaft is provided with a hose coupling 47, that is adapted to couple to one end of a hose or pipe 46, the 15 opposite end of which leads to a supply of compressed air or other suitable drilling engine actuating fluid. To the front or opposite end of this tubular shaft I secure a cutter head 12. This cutter head comprises a hub portion 12^a, which is mounted on and secured to the end of the tubular shaft by any suitable means, and a plurality of arms 12^b, which project from the hub in tangential planes. I preferably illustrate four of these 20 arms arranged at four quarter points of the hub, although more may be used if desired. Each arm is provided with an actuating fluid port 41, which connects with the tubular shaft 13 through the hub 12^a, and this port 25 extends throughout the length of the arm to near its outer end. Each arm of the cutter head is provided with a plurality of rock drilling engines, arranged in a tangential row in the center of the face edge of each 30 arm. These rock drilling engines consist of a row of cylinder bores along the front edge of the length of each arm from close to the center of the hub portion of the cutter head and at a short radial distance to one side of 35 it, and in a tangential line from the center radial position of the inner cylinder to close to the end of each arm, and the drilling engine cylinder at the center of the length of each arm is preferably bored parallel to the 40 axis of the hub and shaft 13, while those drilling engine cylinders toward the outer end of each arm from this central cylinder are bored on an outward diverging angle from the axial center of this central cylinder, 45 and those toward the hub from this central cylinder are bored also at outward diverging angles to the center of this central cylinder, but they incline towards the axial center of the hub and pipe 13. These cylindrical 50 bores comprise a bore 40 and a bore 40^a and a bore 40^b. The bore 40^a separates the bore 40^b, which is the entrance bore, from the bore 40.

An operative hammer piston 43, is reciprocally mounted in the bores 40 and 40^a, and a port 42 extends from the cylindrical bore 40 to the port 41. A chuck 11 is fitted in the entrance bore 40^b, and a rock cutting drill bit or moil 10 is inserted in each chuck in the 60 reciprocal path of the hammer piston of

each cylinder, and the rock cutting drills or moils at the outer ends of the arms are arranged to stand with their cylinders at an outward angle of about 45 degrees to the center of the cutter head and they are extended far enough 70 from the arms to cut a tunnel of enough larger diameter than the cutter head to allow it and its muck catching cylinder 29, which I will presently describe, to be easily operated within said tunnel.

My invention contemplates the use of any type of operative rock drilling engine attached to or formed in the arms of the cutter head. The cutter head is rotated by a motor 26, which is mounted on the frame 15, and is connected by circuit wires 15^a to a supply of electric current. A pinion 51 is mounted on the motor, which meshes with a gear wheel 52, which is mounted on and secured to one end of a shaft 52^a, that is journaled in suitable boxes 52^b, which are secured to the frame 15. A worm pinion 52^c is mounted on and secured to the shaft 52^a, which meshes with a worm wheel 28 that is mounted on and secured to the tubular shaft 13. The cutter head is surrounded by a cylinder or casing 29, which I term the muck catching cylinder. This muck cylinder is attached to the frame 15 by braces 30 and 30^a. This muck catching cylinder has a closed rear head portion, in which a muck discharging aperture 32 is formed at one side, and a trifle above the horizontal center of the cylinder. This muck cylinder is also provided with a man hole 39, closed by a door 39^a, which is arranged and adapted to permit an operator to pass through the cylinder to the cutter head. The muck or rock cuttings made by the rock cutting drill-bits or moils at the breast of a tunnel naturally drop and work into the inside of 105 the bottom of the muck cylinder, and are removed therefrom by a plurality of buckets 31, one of each of which is secured to the side of each arm that faces the direction of rotation of the cutter head arms. These muck buckets comprise substantially V-shaped metal troughs that are secured to the sides of the arms to stand close to the inside surface of the cylinder at a rearward downward angle that will allow the muck to run out of and discharge 110 readily from them when they register with and directly opposite to the discharge aperture in the rear head of the cylinder. These buckets are preferably made of sheet steel, the outer edges of which are cut to conform to the inner wall of the cylindrical portion of the cylinder 29 when laid on the wing or arm of the cutter head 12. The rear edges of the scrapers 31 are straight to conform to the inner wall of the rear disk-like portion of the 115 shield 29. The ends of the scrapers 31, toward the center of the wheel, are turned up to prevent the muck sliding down into the center of the cutter head, and cause it to pass backward through the opening 32, which is 120

located in the upper left-hand quadrant of the cylinder 29, and in the plane of motion of the scrapers 31. The openings 32 are provided with a lip or short chute 32^a to drop the muck well onto the conveyer 33. The scrapers 31 are attached to the wheel 12 by countersunk caps, and these scrapers are also arranged to dip up the muck from the inside bottom portion of the muck catching cylinder, and raise the muck as the cutter head is rotated and discharge it through the discharge aperture 32 of the muck cylinder, from which it falls onto the endless traveling conveyer belt 33, which is arranged at the side of the frames 15 and 17 in alinement with the discharge aperture 32 of the muck cylinder, and by which it is conveyed to the rear of the tunneling machine, and from which it can be deposited in the cars. This feature of my invention may comprise any suitable operative endless conveyer adapted for carrying rock muck; but I preferably use a conveyer arranged in the following manner: The conveyer 33 may be of any suitable type of the endless belt conveyers in use, one end of which is mounted on a drum 33^a that is rotatably journaled on a shaft 33^b, which is mounted on a bracket 33^c, that is secured to and extends laterally from the frame 15. The opposite end is mounted on a drum 33^d, which is secured to a shaft 33^e, that is journaled in boxes 33^f, that are formed on the end of an extension bracket 37, that is formed on the rear end of the supplementary supporting frame 17. The conveyer 33 is driven by the motor 34 through the medium of a sprocket chain 35, which is mounted on sprocket wheels 35^a and 35^b that are secured to the motor and shaft respectively. My improved tunneling machine is operated on railway tracks 50, which are laid on cross ties 51, placed on the floor of the tunnel. It is necessary that some means be provided to follow the cutter head up to and feed it against the breast of tunnels, and I preferably carry out this feature of my invention in the following manner:

I lay a cog or toothed rail 52 on the ties, in which a gear wheel 53 meshes. This gear wheel is secured to one of the axles of the track wheels of the frame 17. This gear wheel is driven by a worm wheel 54 that is mounted on the driving shaft 55 of a motor 38, which is mounted on the supplementary truck frame 17. This motor is operatively connected by circuit wires to a supply of electric current.

The operation of my improved tunneling machine is as follows: The motor is arranged and adapted to move the tunneling machine forward or backward on the cog track and rails toward and against the rock in cutting relation thereto, or away from the breast of the tunnel. Compressed air or any other suitable actuating fluid is supplied to the hose or

pipe 46 and tubular shaft 13, and flows through the ports 41 and 42 to the cylinders 40 and hammer pistons 10, and the hammer pistons are operatively arranged in these cylindrical bores to strike the rock cutting drill-bits or moils. The machine is then fed by the motor against the breast of the tunnel, and the cutter head 12 is rotated through the medium of the motor 26 and the gearing connecting this motor 26 with the shaft 13, and the rock cutting drill bits or moils are driven by the rapid reciprocal strokes of the hammer pistons against the rock breast, and as the cutter head rotates, the said drill bits cut and chip away the rock, which falls to the bottom of the tunnel directly into the muck catching cylinder, or is shoveled into its lower front edge by the forward feeding movement of the machine, and is dipped up by the muck-buckets or scrapers as they rotate with the cutter head, and is discharged from the muck cylinder through its discharge aperture, onto the endless traveling conveyer 33, by which it is carried to the rear end of the machine, from which it drops into cars, which I do not illustrate, but which are run into the tunnel on the track and positioned at the end of the truck frame 17 in position to receive it from the end of the conveyer.

My tunneling machine is adapted not only to drill tunnels but to automatically discharge the muck from the cutter head as it is formed, thus permitting the machine to be fed rapidly and continuously forward in the rock breasts as fast as its rock drilling engines will cut into it.

While I have illustrated the preferred construction and arrangement of my tunneling machine, I do not wish to be limited to it, as many changes might be made without departing from the spirit of my invention.

Having described my invention, what I claim as new and desire to secure by Letters Patent, is:

1. In a rotary tunneling machine, the combination of a supporting frame, a tubular shaft revolvably mounted on said frame, a rotary cutter head secured to one end of said tubular shaft, a plurality of operative rock drilling engines arranged to cut the breast area of a circular tunnel, said cutter head having ports leading from said tubular shaft to said rock drilling engines, means including a motor for rotating said tubular shaft and cutter head, means for connecting the opposite end of said tubular shaft to a supply of suitable drilling engine actuating fluid, a muck catching cylinder on said supporting frame surrounding said cutter head, and means for conveying the muck from said cutter head and cylinder to the opposite end of said supporting frame from said cutter head.

2. In a rotary tunneling machine, a supporting frame, a cutter head rotatably

mounted on one end of said frame, comprising a hub portion provided with a plurality of arms projecting tangentially from said hub, a row of operative rock drilling engines 5 arranged in the face edge of each of said arms at various predetermined angles to the axis of said cutter head, said cutter head having a plurality of ports leading from said hub portion of said cutter head through said 10 arms to said drilling engines, means for connecting said ports to a supply of compressed air, means for rotating said cutter head, means for feeding said cutter head and supporting frame to operatively drill the breast 15 of a tunnel, a muck catching cylinder secured to said supporting frame and surrounding said cutter head, and a conveyer arranged to convey the muck from said cutter head and cylinder to the opposite end of said supporting 20 frame from said cutter head.

3. In a rotary tunneling machine, the combination of a wheeled supporting frame, a tunnel track for said wheeled frame, a cog rail on said track, means including a motor- 25 operated pinion geared to said cog track for moving said frame in a tunnel along said track, a rotary cutter head mounted on said frame, means including a motor for rotating said cutter head, a plurality of operative 30 rock drilling engines in said cutter head arranged at such angles of inclination to the longitudinal axis of said cutter head and frame as will adapt them to cut out the breast area of a circular tunnel of larger di- 35 ameter than said cutter head, a muck catching cylinder supported by said frame and surrounding said cutter head, and provided with a discharge chute, a conveyer mounted on said frame in muck receiving relation to 40 said cylinder's discharge chute, and adapted to convey the rock muck from said cutter head and cylinder to the opposite end of said frame from said cutter head, and muck scrapers on said cutter head arranged to 45 scrape the muck in said cylinder into its discharge chute.

4. In a rotary tunneling machine, the combination of a supporting frame, means including a motor for feeding said frame to and 50 from the breast of a tunnel, a rotary cutter head provided with a hollow axial shaft rotatably mounted on said supporting frame, a plurality of operative pneumatic rock drilling engines and drill bits operatively ar- 55 ranged in said cutter head to drill and cut away the breast area of a circular tunnel of larger diameter than said cutter head, a muck catching cylinder on said frame surrounding the periphery of said cutter head 60 and provided with a muck discharging aperture, a plurality of muck buckets secured to said cutter head in positions to scrape up and discharge said muck through said discharge aperture, and an endless belt conveyer ar- 65 ranged on said frame to receive the muck from

said buckets and discharge aperture and convey it to and discharge it from the opposite ends of said supporting frame from said cutter head.

5. In a tunneling machine, the combination of a two-part wheeled supporting frame, an adjustable joint arranged to connect the two parts in such a manner that one part is adjustable at different angles of inclination to the other part, an operative cutter head attached to the free end of the adjustable part of said frame, a plurality of rock drilling engines operatively supported by said cutter head to drill the breast area of a circular tunnel, means including an endless conveyer 70 belt for conveying the muck from said cutter head to the rear end of said frame, means for rotating said cutter head, and means for feeding said frame and cutter head to operatively drill the breast of a rock tunnel. 75

6. In a tunneling machine, a cutter head provided with a plurality of drilling engines, a hollow supporting shaft secured to said cutter head and connected at one end with a source of fluid under pressure, and at its 80 other end with a plurality of ports in said cutter head leading to the drilling engines, a frame upon which said shaft is rotatably mounted, having a pair of supporting wheels at its forward end, and a coupler at its rear end, a wheel frame having a laterally adjustable pin upon its forward end, which is adapted to be secured within any one of a plurality of holes arranged one above the other in said coupler, a casing surrounding the cutter 85 head, having a discharge opening, a conveyer adjacent to said opening, and means for operating the same, buckets on the cutter head in the path of the opening, means for rotating the cutter head, and means for propelling the rear frame. 90

7. In a tunneling machine, a cutter head comprising a hub and a plurality of arms arranged tangentially to the hub, each arm being provided with a plurality of air receiving cylinders, communicating by separate ports with a common source of air under pressure, hammer pistons in said cylinders and drill bits in line with said pistons, a two-part wheel frame for supporting said cutter head, an adjustable coupling device for uniting the parts of the frame, means for rotating the cutter head, and means for propelling the two-part wheel frame. 100

8. In a tunneling machine, a rotatable head; a plurality of power driven moils in said head, disposed at an angle to the axis of the head; a carriage for supporting the head; means for giving a vertical or a lateral adjustment to the rear end of the carriage; 110 means for propelling the carriage; means for rotating the head; and means for removing the muck, as the carriage advances. 115

9. In a tunneling machine, a rotatable head; a plurality of groups of power driven 120

moils in said head, disposed at an angle toward the direction of rotation of the head, the moils of each group radiating from a common point; a carriage for supporting the head; means for adjusting the rear end of the carriage vertically and horizontally; means for propelling the carriage; means for rotating the head; and means connected with the machine for removing the muck as the carriage advances.

10. In a tunneling machine, the combination with a carriage, having a rotatable, power driven cutter head mounted thereon, and a power driven car, of means for connecting the car with the carriage so as to admit of a lateral and vertical adjustment of the rear end of the carriage relatively to the car; and means connected with the car and carriage for automatically removing the muck as the machine advances.

11. In a tunneling machine, the combination with a carriage; a rotatable power driven cutter head mounted on the carriage; a power driven car connected to the carriage; and means connected with the cutter head for collecting and discharging muck through its rear end as the machine advances; of a chute secured to the carriage in the path of the discharging muck; an endless conveyer supported at one end upon the car, and at the other end upon the carriage so as to lie beneath the chute; and means for operating the conveyer.

12. A rotary tunneling machine, comprising a revoluble cutter head, provided with a plurality of groups of rock chipping machines, the machines of each group being arranged at diverging angles from each other.

13. A rotary tunneling machine, comprising a revoluble cutter head, provided with a plurality of groups of rock chipping machines, the machines of each group being arranged at diverging angles from each other, the machines of each group being positioned to rotate in circular paths between those in which the machines of the preceding group move.

14. A rotary tunneling machine, comprising a rotary cutter head; a plurality of rock dressing machines mounted on said cutter head; a muck catching hood surrounding said cutter head; a plurality of muck scrapers on said cutter head within said hood; a discharge aperture in said hood registering with said muck scrapers; a supporting beam on which said cutter head is revolvably mounted, arranged to support said muck catching hood; an abutment car for said cutter head and its supporting beam; a vertically and horizontally adjustable connection between said car and said cutter head beam; means connected to said car for feeding said car and beam and cutter head forward or backward and against the breasts of tunnels; and a suitable muck conveyer mounted on said car and beam in operative muck receiving relation to said hood's muck discharging aperture, and arranged to convey said muck to the rear of said car.

In testimony whereof I affix my signature in presence of two witnesses.

OLIN S. PROCTOR.
